UNITED STATES PATENT OFFICE.

DELEVAN F. MORGAN, OF CHICAGO, ILLINOIS.

DESIGN FOR A POWER-TRANSMITTING BELT.

57,144.

Specification for Design.

Patented Feb. 22, 1921.

Application filed April 29, 1920. Serial No. 377,723. Term of patent 14 years.

To all whom it may concern:

Be it known that I, DELEVAN F. MORGAN, a citizen of the United States, residing at Chicago, in the county of Cook and State of Illinois, have invented a new, original, and ornamental Design for Power-Transmitting Belts, of which the following is a specification, reference being had to the accompanying drawing, forming a part hereof.

In this drawing:

Figure 1 is a side elevation of the belt;
Fig. 2 is a face view of the same; and
Fig. 3 is a cross-section through the belt
showing my new design.

I claim:

The ornamental design for a power transmitting belt as shown.

DELEVAN F. MORGAN.
